G. J. KELLER ET AL

TUBE FILLING APPARATUS

Filed Mar. 29, 1921

Inventors.
George J. Keller and Otto Buchholz.
By their Attorney, *Frederick C. Fischer*.

UNITED STATES PATENT OFFICE.

GEORGE J. KELLER, OF NEWARK, AND OTTO BUCHHOLZ, OF ELIZABETH, NEW JERSEY.

TUBE-FILLING APPARATUS.

Application filed March 29, 1921. Serial No. 456,668.

To all whom it may concern:

Be it known that we, GEORGE J. KELLER, a citizen of the United States, residing in the city of Newark, county of Essex, and State of New Jersey, and OTTO BUCHHOLZ, a citizen of the United States, residing in the city of Elizabeth, in the county of Union and State of New Jersey, have invented certain new and useful Improvements in Tube-Filling Apparatus, of which the following is a specification.

The main purpose of this invention is to provide an apparatus for filling collapsible or ductile tubes with pastes, and like plastic substances, in a clean, effective and speedy manner.

A further object is to provide means combined with the device, for closing and clinching the open end of the filled tube ready for use in the usual way.

A still further object is to provide an apparatus particularly for the use of individual druggists, enabling them to prepare and dispense prescriptions for ointments and pastes in an approved and sanitary form, the entire structure being easily operated, of relatively low expense to construct and not readily liable to derangement.

These and like other objects are attained by the novel construction, combination and arrangement of parts hereinafter described and shown in the accompanying drawings, forming a material part of this specification, and in which:—

Figure 1 is a top plan view of a filling apparatus made in accordance with the invention, the lever being shown in broken lines in its rear position, and the bearing in section.

Figure 2 is a partial side elevational, partial sectional view, the section being taken on line 2—2 of Figure 1.

Figure 3 is an end view looking from the front.

Figure 4 is transverse sectional view taken on line 4—4 of Figure 1.

Figure 5 is a fragmentary sectional view, taken on line 5—5 of Figure 1, showing the tube closing device.

Stated in brief general terms, the implement comprises a base having at its front end a socket in which is a removable sleeve provided with a nozzle adapted to enter a container, such as a thin pliable tube, made

of tin and having a screw cap at its delivery end.

A split bushing is fitted to the sleeve, into which the plastic material is filled, the bushing also receiving a piston, a stem link connected to a lever pivoted to the base and provided with a manually operable handle.

A fixed angular faced block, secured to the base, acts as an abutment against which the edge of the lever contacts, the same acting co-operatively as a vise for pressing the ends of the filled collapsible tube together, sealing the same.

Referring more specifically to the drawings in detail, the numeral 15 designates an oblong rectangular base adapted to be supported on any convenient level surface.

A pair of opposed longitudinal strips 16 extending in parallel above the surface of the base, between which, entering in the base, is a semi-circular channel 17, the same stopping at an abutment 18 near the front end of the base, the surrounding material being curved outwardly as shown at 19.

At the end of the channel 17 is an integral bearing 17' provided with an opening or guide-way 29' for the stem 29. Located between the end of the channel 17 and the bearing 17' is a curved depression 28' into which the removable piston or plunger fits when it is in the position indicated in dotted lines, in which case the piston or plunger projects approximately half its length from the end of the sections 26 and 26', one half of the piston or plunger (shown in dotted lines) projecting into said sections and the other half of the piston or plunger adapted to be received into said curved depressions 28' and bearing against the inner face of the bearing 17'.

Fitted to the channel is a sleeve 20 of lesser length than the strips, its front end being seated against the abutment 18 and having a thickened interior 21 bevelled outwardly to the main cylindrical bore.

A correspondingly bevelled disc 22 is fitted to the element 21 and formed with the disc is a tapering nozzle or nipple 23, adapted to enter the collapsible tube 25, when held there against, a central orifice 24 passing through the disc and nozzle.

A bushing preferably formed of sections 26 and 26' for enabling the operator to easily fill the same with the substance to be

entered into the collapsible tube, is entered into the sleeve 20, the outer end of the bushing, either split or solid, abutting against the face of the disc 22.

5 A piston or plunger 28 is slidably and removably fitted to the interior of the bushing and is forced forward by means of the end of a stem 29, having a fork 30 at its outer end, this fork being pivotally secured 10 to a link 31, connecting with a lever 32.

This lever 32 is pivoted on a screw 33 set in an extension of the base and is provided with an extending operating handle 34 for manually moving the same.

15 The lever rides freely over a raised ridge 35 on the front of the base and a fixed stop 36 in the base limits its outward motion.

A block 40 is set in the base 15, adjacent the lever fulcrum screw 33, the block being 20 held in position by screws 41 to present a flat angular face 42 so positioned that the adjacent edge of the lever 32 can make intimate contact with it.

In operation, the lever is moved outwardly, 25 permitting the sleeve, nozzle, and bushing to be raised as a unit from its channelled seat, the bushing withdrawing from the sleeve and filled, either partially or wholly with any desired medicament, this being 30 easily accomplished by separating the bushing, after which the parts are replaced, with the removable piston or plunger inserted in the end of the bushing.

The collapsible tube is applied by hand so 35 that its open end opposite the closure or cap is entered over the nipple, the piston directed to enter the bushing and the handle pulled outwardly towards the front, causing the medicament to be extruded through the 40 opening in the disc directly into the tube until it is filled to the desired capacity.

After removing the tube it is held, bottom 45 downward, adjacent the flat face of the block and pressure applied by actuating the lever in an obvious manner.

While certain preferred embodiments of this device have been shown and described, it will be understood that changes in the form, arrangements, proportions, sizes and 50 details thereof may be made without departing from the scope of the invention as defined in the appended claims.

The parts of the apparatus, namely, the sleeve 20, the sections 26 and 26', the piston 55 28 and the stem 29 together with the disc 22 and its attached nipple 23, lend themselves readily to be kept in a clean and sanitary condition. The piston being removable and

separate from the stem, there are no sharp corners or joints which cannot be kept in a 60 clean and sanitary condition.

Having thus described our invention, what we desire to secure by Letters Patent and claim, is:

1. An apparatus for filling collapsible 65 tubes, comprising a base, an open socket formed at the front thereof, an annular sleeve removably engaged in said socket, a nozzle detachably secured in said sleeve, a cylindrical split bushing contained in said 70 sleeve abutting said nozzle; a removable piston in said bushing, a manually operated lever pivoted on said base, and linked connections between said lever and said piston.

2. An apparatus for filling collapsible 75 tubes, comprising a base having a socket disposed therein, a sleeve engageable in said socket, an orificed nozzle engaged in said sleeve, a split bushing engageable in said sleeve abutting said nozzle, a plunger fitting 80 said bushing, a lever pivoted on said base, a stop for said lever, and operative connections between said lever and said plunger.

3. An apparatus for filling collapsible 85 tubes comprising a channelled base, a sleeve disposed in the channel of said base, a nozzle carried by said sleeve, a longitudinally sectional bushing removably engaging said sleeve, a plunger fitting said bushing, a lever on said base, operative connections engaging 90 said lever with said plunger, and a block having a flat diagonal face disposed in the path of said lever.

4. An apparatus for filling collapsible 95 tubes comprising a base, a semi-cylindrical socket formed centrally in the front portion of said base, spaced parallel raised extensions on the sides of said socket, a sleeve adapted to be disposed in said socket, said sleeve having a bevelled contracted front 100 end, means formed with said socket preventing the outward movement of said sleeve, a disc fitting the contracted end of the sleeve, a nozzle formed with said disc, said disc and nozzle having a central passage, a split bushing in said sleeve, a plunger operable in said bushing, and means for manually actuating said plunger.

105 This specification signed and witnessed this 26th day of March, 1921.

GEORGE J. KELLER.
OTTO BUCHHOLZ.
